DESIGN FOR AN EYEGLASS FRAME

Edward W. Smith, Jr., Flushing, N. Y., assignor to Alexander Kono, doing business under the name of Kono Manufacturing Company, Woodside, N. Y.

Application May 23, 1942, Serial No. 106,978

Term of patent 14 years

To all whom it may concern:

Be it known that Edward W. Smith, Jr., a citizen of the United States of America, residing at Flushing, Long Island, in the county of Queens and State of New York, has invented a new,
original, and ornamental Design for an Eyeglass Frame, of which the following is a specification,
reference being had to the accompanying drawing,
forming part thereof.

Fig. 1 is a front elevational view of the eyeglass frame, embodying my new design.

Fig. 2 is a top view thereof.

The characteristic features of my design for an eyeglass frame are the specific configuration
of the lens rims in combination with the nose piece which bulges forward and has upwardly and inwardly inclined upper edges extending from the lens rims.

I claim:

The ornamental design for an eyeglass frame,
as shown and described.

EDWARD W. SMITH, JR.
